UNITED STATES PATENT OFFICE.

CHESTER A. OLMSTEAD, OF EAST BLOOMFIELD, NEW YORK.

BEEHIVE.

No. 850,176.

Specification of Letters Patent.

Patented April 16, 1907.

Application filed May 14, 1906. Serial No. 316,874.

To all whom it may concern:

Be it known that I, CHESTER A. OLMSTEAD, a citizen of the United States, residing at East Bloomfield, in the county of Ontario and State of New York, have invented a new and Improved Beehive, of which the following is a specification.

The object of my invention is to provide a beehive of improved construction whereby there may be raised within the brood-chamber a new queen while the old queen is still doing duty within the hive and that, too, under conditions permitting the new queen to mate, while at the same time preventing any possibility of a meeting between such queens within the brood-chamber.

Another object of my invention is to provide ready means for the inspection of one or more of the brood-frames in the brood-chamber, in which there may be located queen-cells. This is for the purpose of determining the progress of affairs within the hive, and thereby also approximately the time of swarming. The queen-cells are usually located in a brood-frame in practically the center of the hive, and I have usually found it sufficient to make a central brood-frame removable for purposes of inspection, as above noted, and of course when queen-cells are grafted into a brood-frame they may readily be located in the central brood-frame.

Still another object of my invention is to provide an improved ventilating device for the brood-chamber and also a bee-entrance arranged to prevent so far as possible the drifting of snow or extraneous matter into the hive, resulting from a current of air against the bee-entrance.

Still another object of my invention is to provide an arrangement of the section honey-boxes and a separating-fence between them which shall occupy as little space as possible in the super in order that there may be the maximum space within the super for honey.

The accompanying drawings, illustrating a beehive constructed in accordance with my invention, are as follows: Figure 1 is a side view of the hive with a part of the front casing to the right removed from the super and, similarly, with a part of the front casing to the left removed from the brood-chamber, as clearly indicated. Fig. 2 shows a plan view of my hive with the cover only removed from that part thereof to the right of the line $x y$ and with the cover and super removed to the left of such line $x y$. Fig. 3 is a side

view of one of the section honey-box frames, showing the separator-fence and the method of attaching and using the same. Fig. 4 is a top view or plan view of the parts seen in Fig. 3. Fig. 5 is a front view of the bottom board of the hive. Fig. 6 is a vertical sectional view taken through the center of the bottom board. Fig. 7 is a side view of a plain section honey-box frame, such as I make use of between the fenced sections and alternating therewith. Fig. 8 is a side view of one of the brood-frames; and Fig. 9 shows a side view of the central frame arranged to receive the queen-bee cells and shows the device which I employ for rendering such frame removable from the brood-chamber and also the devices which I make use of for excluding the old queen from access to the chamber containing the new queen-cells or the young queen while being reared. It also shows the device permitting the exit of the young queen from this chamber for the purpose of mating, while at the same time preventing a contact between the old queen and the young queen within the hive. Fig. 10 is a left-hand end view of the parts seen in Fig. 9 and with the front casing of the brood-chamber removed. Fig. 11 is a side view, and Fig. 12 a view from the under edge of the frame for carrying the queen-excluding zinc. Fig. 13 is an enlarged end view of the upper and left-hand end of the removable brood-frame.

Similar letters refer to similar parts throughout the several figures of the drawings.

Referring to the drawings, D comprises the bottom of my beehive, upon which there rests the brood-chamber C, with the super B above it and having the removable cover A thereover. The super B contains the section honey-box frames B' and B'', resting upon and supported by a metallic cleat e, secured to the under edge of the front and rear sides of the super B. One of the frames B' for the section honey-boxes is seen in Fig. 7 and comprises the top piece a' and bottom piece a'', between which are secured the end pieces a² and a³. The section honey-boxes a are of such a size that the desired number of them may be forced into the frame B' and held in place by friction therewith and with each other at their junctions.

The frames for the section honey-boxes B'', although quite similar to the frames B', are constructed as follows: To a bottom piece a⁴ there are secured upright pieces a² and e², as

seen in Fig. 4, with the fence *s* firmly secured between them at about its middle point, and then over the joint between the pieces *a*² and *e*² are secured the pieces *e*', extending to the extreme top and bottom of the frame *B*², and therefore one on either side of the bottom piece *a*⁴. The horizontal wires of the separating-fence *s* are then loosely secured between the edges of the upright piece *e*⁴ and the pieces *e*³, secured on the edges thereof. Then the ends of the horizontal wires to the fence *s* are passed around the upright *a*⁵ and firmly secured thereto and clamped between the edges of this upright *a*⁵ and the side pieces *e*⁵ secured thereto. The side pieces *e*³ and *e*⁵ extend downwardly on the outside of the bottom pieces *a*⁴. The upright *e*⁴, which is secured at its lower end to the bottom piece *a*⁴ and at its upper end to the top piece *a*'⁴, is of such a length that when clamped between the uprights *e*² and *e*⁴ the desired number of section honey-boxes will be firmly clamped between the uprights *e*² and *e*⁴ simultaneously with the top piece *a*'. A suitable spring *a*⁷ is provided and preferably secured to the upright *a*⁵, when by the insertion of the wedge *a*⁶ the horizontal wires of the separating-fence *s* may be put under tension and firmly held in place, the whole action being such, as will at once be understood, as to firmly clamp the section honey-boxes *a* between the uprights *e*² and *e*⁴, while the top piece *a*' prevents too great a thrust being exerted in this way upon the section honey-boxes *a*. The spring *a*⁷ operates to hold the horizontal wires of the fence *s* under sufficient tension to keep them straight.

For purposes of economy and convenience it is preferable, although not necessary, that the wires comprising the separating-fence be of ordinary commercial round wire, as less difficulty is experienced in handling such wire or a screen made therefrom. I will mention that I have used the horizontal wires alone, and I have also used horizontal wires and vertical wires interwoven therewith with very good results; but on account of the liability of the vertical wires to be displaced it is desirable that the vertical wires be so interwoven as to present a selvage edge at the top and bottom of the separating-fence. It is also desirable that at least two of the vertical wires be omitted opposite the line of union between the section honey-boxes in order that there may be afforded a ready access for the worker bees from one section honey-box to an adjacent one, and for this purpose the fence *s* is held under tension one-half of a bee-space distant from the outer edges of the section honey-boxes *a*, and the horizontal wires of the fence *s* are preferably at least two-twelfths, and they may advantageously be one-fourth of an inch apart, it being necessary to provide the usual bee-space of at least two-twelfths of an inch be-

tween the side edges of the section honey-boxes in one frame and those of the adjacent frame in order that there may be afforded an opportunity for the bees to pass from one section honey-box to another adjacent one, 70 and this therefore necessitates the omission of the vertical wires in the fence *s* at and for a short distance each side of the adjacent edges of the section honey-boxes in each frame. The horizontal wires of the separating-fence being far enough apart to permit the bees to pass between them, it is then possible to economize space by locating the section honey-box frames *B*' and *B*² at such a distance apart that the side edges of the section honey-boxes in the frame *B*' will be distant from those in the adjacent frame *B*² on each side just two-twelfths of an inch to permit the bees to pass to and from the several section honey-boxes in the frames. I will 85 mention that two-twelfths of an inch comprise a bee-space.

I desire to call especial attention to the advantages resulting from my construction and arrangement of a separating-fence, in 90 that the fence being held under tension it is held straight and it cannot sag or become warped, so as to obstruct the passage of the bees from any one section honey-box to another, as often occurs in the use of the ordinary separating-fence comprising sheets of 95 perforated metal or metal-bound wire screens.

I will now describe my improved bee opening or entrance to the hive. *D* is the bottom board. *d* is a cleat secured on the under side thereof and cut away partially, so as to present an opening *d*³, extending inwardly from the outer edge thereof and connecting with an opening *d*⁵, extending upwardly through the bottom board *D*. Hinged to this bottom board *D* is seen a swinging flap *d*⁶, arranged when in its downmost position to rest against the screen *d*⁴ and close the opening *d*³ through the bottom cleat *d*. Secured to the under side of this bottom board *D* are seen the cleats *d'* and *d''*, arranged to reinforce or thicken this board *D* around on all of its edges. This bottom board *D* may preferably be built up in sections of matched lumber secured to the cleats *d'*. The construction and arrangement of the parts just described is for the following purpose: When the wind blows toward the hive, it passes through the opening *d*³ and through the screen *d*⁴, secured on the back side of the cleat *d* and to the rear wall of the opening *d*⁵, forcing the hinged flap *d*⁶ to the rear, and any snow or extraneous matter that would otherwise be forced upwardly through the opening *d*⁵ and into the brood-chamber *C* is allowed to 125 pass outwardly through the screen *d*⁴. This flap *d*⁶ is closed by a current of air in the opposite direction.

To provide for the ventilation of the hive, I secure a screen *o* over a suitable opening in 130

the bottom D, and the portion of the bottom D to the left of the opening is beveled downwardly to the rear, as indicated, and coöperating therewith is seen the removable section 5 o', tongued and grooved into the rear section d' of the bottom board D in such a way that when this beveled section o' is forced slightly to the left its right-hand edge may be withdrawn downwardly and out from the bottom 10 board, so as to permit the entrance of air up through the opening thus formed in the bottom board and through the screen o, covering the same. I prefer to make use of a thin slide o³, supported on cleats o⁴ and adapted to 15 entirely cover the opening through the bottom board D on the under side, and so held in place by a spring o² that this strip o³ may be forced to the left when it is desired to remove the beveled section o' from the bottom 20 D, and when moved to the right, as shown in Fig. 6, it serves to close entirely the opening through the bottom board D from the under side and the joints between the parts just described and prevents the entrance of cold air. 25 I will now describe the construction and arrangement of brood-frames which I prefer to make use of in the brood-chamber C and the conformation and arrangement of parts whereby I secure the above-mentioned desirable results in permitting the rearing and 30 mating of a new or young queen while the old queen is still doing duty within the hive. At the upper edge of the front and rear sides of the brood-chamber I provide metallic cleats 35 c³, having notches therein adapted to receive the bent supporting-wires c⁴, secured in the ends of the brood-frames C² and at approximately their upper edges. These supporting-wires c⁴ are so conformed that their projecting upper edges are approximately on the same level with the top edges of the brood-frames C², and to accommodate these supporting-wires c⁴ the front and rear sides of the brood-chamber are rabbeted at their upper 40 edges, as indicated in Fig. 9, and when the brood-frames C' are all in place cleats c⁵ are inserted over the supporting-wires c⁴, forming a level surface with the top edge of the front and rear sides of the brood-chamber 45 to receive the bottom edge of the super B. By the use of the metal cleats c³ and the supporting-wires c⁴ the cementing of the parts together by the bees is prevented. 50

In the front wall of the brood-chamber I provide a removable portion C', arranged to be normally held in place by the buttons c' and preferably beveled on its edges to fit the correspondingly-beveled edges of the opening in the front of the brood-chamber C, and upon the removal of this section C' the center one of the brood-frames is removable for purposes of examination, &c., as will be explained. This central brood-frame comprises a top piece C³, which may preferably 55 be longer than the top pieces of the remain-

ing brood-frames; but it is supported in substantially the same way by means of the supporting-wires c⁴. This top piece C³ is rabbeted on its edges, as indicated in Figs. 10 and 13, and has secured within the rabbets 70 thus formed angular supporting-cleats n, adapted to engage the bar n', preferably of metal, secured to the top bar c⁶ of the removable brood-frame. This top piece c⁶ and the metal bar n', secured on the upper edge 75 thereof, is, as shown in Fig. 9, somewhat beneath the top of the opening in the front wall of the brood-chamber C, normally closed by the removable section C', and this opening thus formed by the removal of the section C' at its bottom is slightly below the bottom piece c⁹ of the removable brood-frame. The removable section of the brood-frame comprises the front and rear end bars c⁷ and c⁸, secured to the bar c⁶ at their upper ends 80 and also to the bar c⁹ at their lower ends, and between the top bar c⁶ and the bottom bar c⁹ there may be secured one or more bars, such as c¹⁰, for the purpose of providing a compartment within which there may be reared a 85 new queen and for which purpose I provide, further, the device to be described. 90

It is well known that bees in working are apt to cement or glue contiguous parts in the hive together, and it is necessary, therefore, to provide means which will prevent the gluing of the removable section of the central brood-chamber from its supporting-bar C³. This I accomplish in the following manner: I provide spring-plates n², adapted to extend over 95 and cover the joint formed between the angular cleats n and the bars n' in such a way as to present a fine spring edge adapted to press firmly against the top piece c⁶ of the removable section, as the bee-glue will not adhere firmly enough to the metal spring-plates n² to prevent the withdrawal of the top plate c⁶ of the removable section of the brood-frame by sliding between them. These spring-plates n² may preferably be formed 100 integrally with the retaining-cleats n, as shown in Fig. 10 and in an enlarged view in Fig. 13. Between the left-hand end piece c⁷ of the removable section of the central brood-frame and the vertical member c¹⁰, inserted 105 between the top piece c⁶ and the bottom piece c⁹, there is formed a compartment C⁴, and within this compartment thus formed 110 there may be reared a young queen while the old queen is still doing duty within the hive 115 by resorting to the following devices: Within this compartment C⁴ there is contained the usual foundation-comb, in which there may be grafted the usual wooden cell or a queen-cell, and then the compartment is closed by 120 means of the queen-excluding frame C⁵, comprising top, bottom, and side pieces, to which there is secured the queen-excluding zinc C⁶, the openings in which permit the ingress and 125 egress of worker-bees, while excluding the old 130

queen. This frame C^5 comprises the side pieces t , t' , t^2 , and t^3 , the front side t being rabbeted, as shown, to prevent its going too deeply into the compartment C^4 , and for this purpose there are also provided the stops t^4 on the top piece t^2 and bottom piece t^3 of this removable queen-excluding frame C^3 .

Retaining-buttons t^5 are provided to hold the frame C^5 in place. An opening t^6 is provided through the end pieces c^7 of the removable section of the central brood-chamber and partly through the side t of the queen-excluding frame C^5 to permit the young queen to pass out from the chamber C^4 for the purpose of mating, in doing which she passes out of this opening t^6 and through the opening c^2 , which for this purpose has a metal tube t^7 extending inwardly toward the end piece c^7 of the removable section of the brood-frame far enough to prevent ingress and egress from the brood-chamber C to the chamber C^5 .

When it is desired for any purpose to remove the central brood-chamber, the buttons c' are turned and the section C' of the front of the brood-chamber C is removed by grasping with the thumb and finger the front piece c^7 of the removable section of the central brood-chamber. Such removable section may be removed by drawing the same outwardly.

When a new queen is started in the compartment C^4 , the worker bees have access thereto through the queen-excluding zinc C^6 , and in this way the queen is reared, and by removing the removable section of the central brood-frame the progress of affairs in the hive may be readily learned. The young queen is permitted to pass out through the opening c^2 and the tube c^7 therein for the purpose of mating at the proper time.

For the purpose of preventing the brood-frames C^2 from swinging to and fro at their lower edges when the hive is moved I provide a retaining device comprising a rod r , as shown in Figs. 1, 2, 9, and 10, extending from one side of the brood-chamber C to the other and journaled in the side walls of the brood-chamber and at their lower edges. This rod or wire r is bent to and fro, so that it may be turned to lie flat and extend wholly beneath the brood-frames C^2 , or it may be turned up, so that the projections formed therein will come between the brood-frames C^2 and serve to keep them properly spaced at their lower edges.

What I claim is—

1. In a beehive, an entrance comprising a passage-way extending upwardly through the bottom and within the brood-chamber and connecting therewith a passage-way extending in an approximately horizontal direction through a downward projection carried by the bottom and such last-named passage-way closed on its rear side by a hinged

flap adapted to be opened by a current of air directed toward the opening from without the hive and adapted to be closed and held closed by a current of air in an opposite direction.

70

2. In a beehive, an entrance comprising a passage-way extending upwardly through the bottom and within the brood-chamber and connecting therewith a passage-way extending in an approximately horizontal direction through a downward projection carried by the bottom and a screen extending over the rear opening in such last-named passage-way.

75

3. In a beehive as a means for ventilating the brood-chamber thereof, an opening through the bottom of the hive having one of its walls extending obliquely downward and inwardly and coöperating therewith a correspondingly-beveled section adapted to close such opening and removable therethrough, means for supporting such beveled section in operative position closing such opening and a member slidably supported on the under side of such bottom and adapted to cover the joints between such opening and such coöperating beveled section.

80

4. In a beehive, a separating-fence between adjacent section honey-box frames comprising a series of horizontally-disposed wires and means for supporting the same under tension between such section honey-box frames, and means for adjusting the tension on such wires.

85

5. In a beehive, a separating-fence between adjacent section honey-box frames comprising a series of horizontally-disposed wires and means for supporting the same under tension between such section honey-box frames and means for adjusting the tension on such wires, such wires comprising the horizontal wires of a wire screen.

90

6. In a beehive, a separating-fence between adjacent section honey-box frames comprising a series of horizontally-disposed wires and means for supporting such wires under tension on one of such frames and between such frame and an adjacent frame and means for adjusting the tension on such wires.

95

7. In a beehive, a separating-fence between a section honey-box frame and an adjacent one on each side thereof comprising a series of horizontally-disposed wires and means for supporting such wires under tension on such section-frame and between such section-frame and such adjacent frame on each side thereof and means for adjusting the tension on such wires.

100

8. In a beehive, a separating-fence between a section honey-box frame and an adjacent one on each side thereof comprising a series of horizontally-disposed wires and means for supporting such wires under tension on such section-frame and between such

105

section-frame and such adjacent frames on each side thereof, such wires adapted and operating to clamp the section honey-boxes together in such frame on which they are supported.

5 9. In a beehive, a separating-fence between a section honey-box frame and an adjacent one on each side thereof comprising a series of horizontally-disposed wires and means for supporting such wires under tension on such section-frame and between such section-frame and such adjacent frames on each side thereof, such wires adapted and operating to clamp the section honey-boxes together in such frame on which they are supported and means for adjusting the tension on such wires.

10 10. In a beehive, a series of section honey-box frames and between them a series of separating-fences and means carried by alternate ones of such frames for supporting such separating-fences between each one of such alternate frames and an adjacent frame on each side thereof.

11 11. In a beehive, a removable section in one of the side walls of the brood-chamber and independent of such removable section a removable brood-frame adapted to be withdrawn outwardly from such brood-chamber through the opening formed by the removal of such removable section in the side wall thereof.

12 12. In a beehive, a removable section in one of the side walls of the brood-chamber, adapted to be withdrawn from the brood-chamber through the opening formed by the removal of such removable section a brood-frame comprising top, bottom and end pieces, such top piece carrying a guide-plate, coöperating with such guide-plate guiding and supporting bars carried by a member supported within the brood-chamber and also carried by such member metallic cleats adapted, when such removable brood-frame is in position in the brood-chamber, to cover such guide-plate on the top piece thereof and also to cover such guiding and supporting bars and to engage with their lower edges the top piece of such brood-frame and adapted to cover and to prevent a cementing together by the bees of such top piece, guide-plate and guiding and supporting bars.

13 13. In a beehive, a removable section in one of the side walls of the brood-chamber, adapted to be withdrawn from the brood-chamber through the opening formed by the removal of such removable section a brood-frame comprising top, bottom and end pieces, such top piece carrying a guide-plate, coöperating with such guide-plate guiding and supporting bars carried by a member supported within the brood-chamber and also carried by such member metallic cleats adapted, when such removable brood-frame is in

position in the brood-chamber, to cover such guide-plate on the top piece thereof and also to cover such guiding and supporting bars and to engage with their lower edges the top piece of such brood-frame and adapted to cover and to prevent a cementing together by the bees of such top piece, guide-plate and guiding and supporting bars, in such removable brood-frame a compartment adapted to receive queen-cells, such compartment closed by a queen-excluding screen removably secured thereto and a passage-way from such compartment outwardly through the side wall of such brood-chamber, such passage-way permitting a queen bee in such compartment to leave and enter the same and adapted to prevent a contact within the brood-chamber between a queen in such compartment and a queen in such brood-chamber outside of such compartment.

14 14. In a beehive and in the brood-chamber thereof, a brood-frame having therein a compartment adapted to receive queen-cells, such compartment closed by a queen-excluding screen and a passage-way from such compartment outwardly through the side wall of such brood-chamber adapted to prevent a contact within the brood-chamber between a queen in such compartment and a queen in such brood-chamber outside of such compartment.

15 15. In a beehive and in the brood-chamber thereof, a brood-frame having therein a compartment adapted to receive queen-cells, such compartment closed by a queen-excluding screen removably secured thereto and a passage-way from such compartment outwardly through the side wall of such brood-chamber adapted to prevent a contact within the brood-chamber between a queen in such compartment and a queen in such brood-chamber outside of such compartment.

16 16. In a beehive, means for supporting the brood-frames in the brood-chamber thereof, comprising supporting-wires extending outwardly from the upper corners of such brood-frames and metallic cleats supported near the upper edges of opposite side walls of such brood-chamber and having notches therein adapted to receive the supporting-wires in such brood-frames and suitable bars adapted to rest upon the upper edges of such cleats and supporting-wires and adapted to hold such supporting-wires in place and to cover and prevent the filling up or cementing of the space between such supporting-wires and between such cleats and the adjacent side walls of such brood-chamber.

17 17. In a beehive, for spacing and holding the bottom bars of the brood-frames in the brood-chamber a spacing device pivotally supported and adapted to be moved when desired to an inoperative position beneath the bottom bars of such brood-frames.

18 18. In a beehive, a series of section honey-

- box frames each adapted to receive and support two or more section honey-boxes independently of any other one of such section honey-box frames and with the open ends of the section honey-boxes in each frame facing the open ends of the section honey-boxes in an adjacent frame, a separating-fence between the open ends of the section honey-boxes in adjacent frames comprising a series of horizontally-disposed wires and means for supporting the same between such section-box frames under longitudinal tension operating to oppose a lateral movement of such wires. 19. In a beehive, a series of section honey-box frames each adapted to receive and support two or more section honey-boxes independently of any other one of such section honey-box frames and with the open ends of the section honey-boxes in each frame facing the open ends of the section honey-boxes in an adjacent frame, a separating-fence between the open ends of the section-boxes in adjacent frames comprising a series of horizontally-disposed wires and means for supporting the same between such section-box frames under longitudinal tension operating to oppose a lateral movement of such wires, such wires comprising the horizontal wires of a wire screen. 20. In a beehive, a series of section honey-box frames each adapted to receive and support two or more section honey-boxes independently of any other one of such section honey-box frames and with the open ends of the section honey-boxes in each frame facing the open ends of the section honey-boxes in an adjacent frame, a separating-fence between the open ends of the section-boxes in one frame and the open ends of the section-boxes in an adjacent frame comprising a series of horizontally-disposed wires and means for supporting such wires under tension on such frame and between such frame and such adjacent frame. 21. In a beehive, a series of section-honey-box frames each adapted to receive and support two or more section honey-boxes independently of any other one of such section honey-box frames and with the open ends of the section honey-boxes in each frame facing the open ends of the section honey-boxes in an adjacent frame, a separating-fence between the open ends of the section-boxes in one frame and the open ends of the section-boxes in adjacent frames on each side comprising a series of horizontally-disposed wires and means for supporting the same under tension on such section-frame and between such section-frame and such adjacent frames on each side thereof. 22. In a beehive, a separating-fence between the open ends of adjacent section honey-boxes comprising a series of horizontally-disposed wires and means for supporting the same under tension between such section honey-boxes and means for adjusting the tension on such wires. 23. In a beehive, a separating-fence between the open ends of adjacent section honey-boxes comprising a series of horizontally-disposed wires and means for supporting the same under tension between such section honey-boxes and means for adjusting the tension on such wires, such wires comprising the horizontal wires of a wire screen. 24. In a beehive, a removable section in one of the side walls of the brood-chamber and independent of such removable section a removable brood-frame adapted to be withdrawn outwardly from such brood-chamber through the opening formed by the removal of such removable section in the side wall thereof, such brood-frame having therein a compartment adapted to receive queen-cells, such compartment closed by a queen-excluding screen and a passage-way from such compartment outwardly through the side wall of such brood-chamber adapted to prevent a contact within the brood-chamber between a queen in such compartment and a queen in such brood-chamber outside of such compartment. 25. In a beehive, a removable section in one of the side walls of the brood-chamber and independent of such removable section a removable brood-frame adapted to be withdrawn outwardly from such brood-chamber through the opening formed by the removal of such removable section in the side wall thereof, such brood-frame having therein a compartment adapted to receive queen-cells, such compartment closed by a queen-excluding screen and a passage-way from such compartment outwardly through the removable section in the side wall of such brood-chamber adapted to prevent a contact within the brood-chamber between a queen in such compartment and a queen in such brood-chamber outside of such compartment.

CHESTER A. OLMSTEAD.
